Primary Examiner—Nelson C. Holtje(74) *Attorney, Agent, or Firm*—Jean C. Edwards;
Dickinson Wright PLLC(57) **CLAIM**

The ornamental design for an enclosure for a sweeper vehicle, as shown and described.

DESCRIPTION

FIG. 1 is a perspective view showing an enclosure for a sweeper vehicle with front foot panels thereof, according to one embodiment of my new design;

FIG. 2 is a front view thereof;

FIG. 3 is a rear view thereof;

FIG. 4 is a side view thereof; and,

FIG. 5 is another side view thereof.

The elements shown in phantom lines do not form any part of the design of the present invention.
